UNITED STATES PATENT OFFICE.

EUSEBE MIGNAULT AND GEORGE A. PRICHARD, OF NEW YORK, N. Y.

VENTILATOR.

SPECIFICATION forming part of Letters Patent No. 374,987, dated December 20, 1887.

Application filed March 21, 1887. Serial No. 231,637. (No model.)

To all whom it may concern:

Be it known that we, EUSEBE MIGNAULT and GEORGE A. PRICHARD, of New York city, county and State of New York, have 5 jointly invented certain new and useful Improvements in Ventilators, of which the following is a full, clear, and exact description, reference being had to the accompanying drawings, and to the letters of reference marked to thereon.

Our invention has relation to ventilators, especially such as are employed in connection with cars for the purpose of producing an exhaustion of foul air or gases therefrom; but 15 our improved ventilator may be applied in other situations where like exhausting effects are desired.

The object of our invention is to produce a 20 ventilator which is operated by wind or air currents, to which the ventilator is exposed, either when at rest, as by passing wind or air currents, or when the ventilator is moving rapidly through the air, or under both circumstances combined, which ventilator shall produce a positive, rapid, and thorough exhaustion 25 of air or gases from the compartment to be ventilated by mechanical means, and which shall operate easily, noiselessly, and with little friction, no matter in which direction it 30 may be moved nor from which direction the air-current may proceed. To accomplish all this our improvements involve certain new and useful peculiarities of construction and relative arrangements or combinations of parts, 35 which will be herein first fully described, and then pointed out in the claims.

In the accompanying drawings, forming 40 part of this specification, Figure 1 is a view in side elevation showing our improved ventilator, the view being taken of the side opposite the inlet pipe or conduit which leads from the car or compartment to the ventilator. Fig. 2 is a longitudinal sectional elevation of the same. Fig. 3 is a cross-section and elevation upon a plane through line $x x$ of Fig. 2. Fig. 4 is an end elevation. Fig. 5 is a cross-section and elevation upon a plane through line $y y$ of Fig. 2.

In all the figures like letters of reference, 45 wherever they occur, indicate corresponding parts.

A is the main shell of the apparatus, which is of general cylindrical form, having open ends provided with flaring mouths B B, to catch and direct large volumes of air. In the 55 axis of the shell is a shaft, C, mounted so as to revolve easily in the bearings a a, which are made adjustable, so as to compensate for any wear, and which are sustained in suitable arms, b b, connected with the shell. Upon 60 this shaft are mounted and secured two operating-fans, D D, the blades of which are turned or inclined in the same directions, so that any air-current striking both fans will turn them in the same direction or so that one shall not 65 operate against the other. These fans are mounted near the ends of the shaft, and it is immaterial in which direction they be turned. About the middle part of the shell is a compartment formed by the two division-plates 70 c c'. In this compartment is located an exhaust-fan keyed to shaft C, and the inlet tube or conduit F connects with the compartment to deliver foul air and gases to the fan E, a central division-plate, d, operating to direct 75 the incoming air and gases to the center of the fan, for which purpose the said division is centrally perforated, as shown in Figs. 2 and 3. G is the outlet opening or discharge, through which the foul air and gases are forcibly and 80 rapidly driven by the fan, producing a correspondingly forcible exhaustion from the compartment to be ventilated.

The fan E is driven rapidly by the fans D D. It is desirable that the fans D D should 85 be acted upon by air-currents on both sides. We therefore supply the casing with a number of perforations, e e, outside the central compartment, and guard these by oppositely-inclined flanges H H, about the same 90 size as the flaring mouths B B. Within the casing are conical directors I I, arranged to direct air-currents against the inner faces of both fans D D. The arrangement is such that if the device be moving in either direction, or 95 if it be exposed to a current blowing in the direction of its length, or nearly so, one of the mouths B will direct the current against the outer face of the adjacent fan, the adjacent flange H will prevent the current from impinging against the inner face of this fan, assisting rather in the outflow through perfora- 100

tions *e e* of the air which has passed the fan, the next flange *H* will catch and direct the current against the inner face of the other fan *D*, and the other flaring mouth *B* will assist 5 in exhausting the air which has passed the last fan. Thus the two fans are made to operate simultaneously upon the shaft *C* and to the best possible advantage for the purposes intended.

10 *K K* are reservoirs, which may contain a supply of oil for the journals *a a*, pipes, as at *f*, having suitable couplings, as *g g*, being used to connect the reservoirs with the bearings, and the flow of oil being facilitated by a wick 15 in the pipe *f*.

The improved ventilator may be mounted upon the top or bottom of the car or upon the side, or connected with one of the window-openings. Wherever located, pipes may lead 20 to it from the region of the bottom of the car, if required. It has been found in practice to admirably answer the purpose or object of the invention, as previously set forth.

Having now fully described our invention,

what we claim as new herein, and desire to secure by Letters Patent, is—

1. In a ventilator of the character herein set forth, the combination of the perforated shell, the interior conical air-directors, the exhaust-fan, and the two driving-fans mounted 30 on the same shaft and on opposite sides of the exhaust-fan, substantially as shown and described.

2. In a ventilator of the character herein set forth, the combination of the exhaust-fan, 35 the two driving-fans mounted on the same shaft, and the perforated shell having the flaring mouths, the oppositely-inclined flanges, and the interior conical air-directors, substantially as shown and described.

In testimony that we claim the foregoing we have hereunto set our hands in the presence of two witnesses.

EUSEBE MIGNAULT.
GEORGE A. PRICHARD.
